SANDING MACHINE

David S. Oakley, Bristol, Tenn.

Application January 22, 1934, Serial No. 707,821

2 Claims. (Cl. 51—143)

The invention relates to a sanding machine and more especially to a double belt sander and polisher for flat surfaced and irregular-shaped wood material.

5 The primary object of the invention is the provision of a machine of this character, wherein a pair of sanding belts of the endless or continuous kind are supported side by side and are adjustable toward or away from each other in this 10 position and are susceptible of travel in the same or reverse directions, one with respect to the other, so that the work or material to be operated upon, either solid, veneered, flat faced or irregular shaped, can be sanded and polished 15 to give to such material a smooth and a finished surface, the sanding and polishing operation being carried forth with rapidity and accuracy and without manual labor, as the machine is automatically operated and is susceptible of adjustment 20 so as to have it operate true.

Another object of the invention is the provision of a machine of this character, wherein a number of controls are in association therewith so that the work to be operated upon can be brought into position with accuracy for the sanding of the same and also the polishing thereof and the parts of the machine can be properly set for the efficient operation of the same. Additionally, the sanding and polishing elements will 25 be assured of a maximum life in the use thereof in the machine.

A further object of the invention is the provision of a machine of this character, wherein the sanding and polishing elements can be readily introduced and removed to and from the machine as the power and guide pulleys for the same are susceptible of movement by controls, whereby they may be separated to permit the removal of the sanding and polishing elements or the introduction of the same and also the positioning of these elements with relation to each other so that the work confronting them can be subjected to coarse or fine sanding action according to the requirements in the finishing of such work.

40 45 A still further object of the invention is the provision of a machine of this character, wherein adjustments may be had of all coating parts for the successful and accurate working of the machine both in the presentation of the sanding elements to the work and the presentation of the work to such elements during the operation of the machine.

A still further object of the invention is the provision of a machine of this character which is 50 comparatively simple in its construction, thor-

oughly reliable and efficient in its operation, susceptible of positive control, capable of minute adjustment for accuracy in the working of such machine, strong, durable, and comparatively inexpensive to manufacture.

5 With these and other objects in view, the invention consists in the features of construction, combination and arrangement of parts as will be hereinafter more fully described in detail, illustrated in the accompanying drawings, which 10 disclose the preferred embodiment of the invention, and pointed out in the claims hereunto appended.

In the accompanying drawings:

Figure 1 is a side elevation of a machine constructed in accordance with the invention.

Figure 2 is a fragmentary side elevation of one end portion of the machine and the same being partly in section.

Figure 3 is a fragmentary end elevation showing certain parts broken away and sectioned for illustrating detail adjuncts.

Figure 4 is a fragmentary plan view partly in section of that portion shown in Figure 2, with the electric motor detached.

Figure 5 is an enlarged fragmentary vertical transverse sectional view through the other end portion of the machine and showing certain of the parts in elevation.

Figure 6 is a plan view thereof.

Figure 7 is a fragmentary sectional view on the line 7—7 of Figure 6 looking in the direction of the arrows.

Figure 8 is a fragmentary sectional view on the line 8—8 of Figure 6 looking in the direction of the arrows.

Figure 9 is a fragmentary sectional view on the line 9—9 of Figure 6 looking in the direction of the arrows.

Figure 10 is a fragmentary detail sectional view on the line 10—10 of Figure 8 looking in the direction of the arrows.

Figure 11 is a fragmentary enlarged side elevation, partly vertically sectioned, of the work supporting parts of the machine.

Figure 12 is an end elevation thereof and partly in section.

Figure 13 is a sectional view on the line 13—13 of Figure 11 looking in the direction of the arrows.

Figure 14 is a fragmentary top plan view of one of the sliding tracks of the work supporting section and fitted therein.

Figure 15 is a fragmentary vertical transverse sectional view on the line 15—15 of Figure 12.

Figure 16 is a fragmentary side view showing in detail the table stop as indicated in Figure 15.

Figure 17 is a top plan view of one of the track guideway pieces.

5 Figure 18 is a top plan view of one of the slideable tracks.

Figure 19 is a side view thereof.

10 Similar reference characters indicate corresponding parts throughout the several views in the drawings.

15 Referring to the drawings in detail, the machine comprises the end power motor and guide pulley stands A and B, respectively, and the intermediate work supporting stand C, these being hereinafter fully described in detail.

20 The power motor stand A has arranged thereon the opposed stationary and shiftable electric motors 10 and 11, respectively, each being of a standard reversible type and individually controlled through push button start and stop switches 12 and reverse drive switches 13, respectively, these being suitably positioned adjacent to the shiftable motor 11 for manual control by the operator of the machine. The driving shafts 14 of the motors 10 and 11 have fixed thereto, inwardly of said motors, power pulleys 15 which are of sufficient weight to function indirectly as fly wheels and support endless sanding belts 16 and 17, respectively, arranged side by side or edge to edge, and one of these is a coarse sander and the other a fine sander.

25 The stationary motor 10 is superimposed upon the bearing 18 unitary with the stand A, while the shiftable motor 11 is superimposed upon a slide base 19 fitted within guides 20 formed with the stand A, one guide being fitted with a removable or replaceable wear piece 21. Carried by the slide base is a toothed rack 22 having meshing therewith a rack pinion 23 on a turning stem 40 journaled in said stand A and having one end extended beyond the said stand, to which is fitted a hand wheel 25 for the manual turning of said stem 24 and in this manner the slide base 19 can be moved to shift the motor 11 toward or away from the stationary motor 10, as should be clearly apparent. The base 19 is provided with a slot 26 in which is fitted a binding or set screw 27, the same being threaded into the stand A and such screw is for the purpose of locking the base 19 in its adjusted position, as will be apparent.

30 The pulleys 15 have resilient anti-slipping tread or peripheral contact surfaces 28 to prevent the slipping of the belts 16 and 17 thereon, these belts being formed with the inner sanding surfaces 29.

35 The stand B supports the opposed lightweight adjustable guide pulleys 30, each preferably made from aluminum and having its hub 31 equipped with ball bearings 32, and trained over these pulleys 30 are the belts 16 and 17, the peripheries of the said pulleys being provided with the resilient anti-slipping or frictional contact surfaces 33 for the said belts. The journals 34 for the pulleys 30 are supported in bearings 35, each swinging on a center pivot 36 for arcuate adjustment thereof. The pivot 36 for one bearing is carried by a slide base 37 movably fitted transversely in a shiftable rail 38 which is mounted on the base A for longitudinal displacement, while the other pivot 36 for the other bearing 35 is mounted directly on the other shiftable rail 39 companion to the rail 38. Each rail 38 and 39 carries a toothed rack 40 for meshing engagement with the respective rack pinions 41 on the turning

45 stems 42 and 43, respectively, the latter being suitably journaled in the stand B and having at their outer projected ends the hand wheels 44 so that the same can be manually turned for the shifting of the rails 38 and 39 which function to move the bearings for the tightening of the belts 16 and 17 on the pulleys 15 and 30, respectively. The slide base 37 has journaled therein a turning stem 45 having at its outer end the hand wheel 46 and at its inner end the rack pinion 47 which meshes with a toothed rack 48 fixed to the rail 38 and thus it will be seen that by turning the stem 45 the slide base 37 can be shifted to bring the bearing 35 carried thereby toward or away from the other bearing 35 opposite thereto. 50 The slide base 37 has formed therein the slot 49 accommodating a set screw 50 so that the said base 37 can be made fast in its adjusted position on the rail 38. Each bearing 35, at opposite sides of the pivot 36 therefor, has formed therein the arcuate slots 51 receiving the set screws 52 which are engaged in the base 37 so that when the said bearings 35 are turned in the pivot 36 they can be locked in their turned position and the purpose of the turning of the bearings 35 is to align the pulleys 30 with the pulleys 15 so that the said belts 16 and 17 thereon will travel through and align parallel with each other.

55 Swiveled in the base 37 is a screw mount 53 carrying the adjusting screw 54, the same being threaded into a swiveled connection 55 on the bearing 35 and thus it will be seen that by turning the screw 54 the said bearing can be turned, it being understood, of course, that the set screws 52 have been loosened. The other bearing 35 has the screw mount 56 swiveled on the rail 39 and the adjusting screw 57 engaged in this mount and also in the swiveled connector 58 carried by the said bearing 35 alike to the connection 55 so that on adjustment of this screw 57 the bearing 35 affected thereby can be turned on its pivot 36 and in this fashion both bearings can be accurately set with relation to each other for the parallel aligning of the belts 16 and 17, as should be obvious.

60 The set screws 59 alike to the screws 52 are engaged in the rail 39 and in contradistinction to the engagement of the screws 52 in the base 37.

65 The work supporting stand C includes a pair of spaced leg pieces 60 in which are fitted adjustable uprights 61, each working in a guideway 62 formed in its companion leg piece 60 and carrying a toothed rack 63 meshing with a rack pinion 64 fixed to a driven shaft 65 journaled in the leg pieces 60, so that said uprights 61 can be moved in unison vertically. The shaft 65 carries a worm gear 66 meshing with a worm screw 67 on a turning stem 68, the same being journaled in a center web 69 between the leg pieces 60 and a bracket 70 and carrying at its outer end a hand wheel 71 so that the stem can be manually turned for the adjustment of said uprights.

70 The uprights 61, at their upper ends, are formed with heads 72 to which are made fast guides 73 for movable tracks 74 having the treads 75 engaged by the wheels 76 and 77, respectively, of a movable carriage 78, the wheels 76 being peripherally grooved, while the wheels 77 have straight peripheries, and such wheels have their traction on the treads 75 of the tracks 74. The carriage 78 has arranged thereon the slatted work bed 79 for accommodating work to be acted upon by the sanding belts 16 and 17. The tracks 74 are formed with the upstanding hangers 80 for toothed racks 81, with which mesh the rack pin-

ions 82, these being fixed to a shaft 83 journaled in bearings 84 carried by the guides 73, the shaft 83 being fitted with a beveled gear 85 meshing with a beveled pinion 86 on a turn shaft 87 journaled in brackets 88 fixed to one of the guides 73, the shaft 87 at its outer end being fitted with a hand crank 89 so that it can be manually turned for the shifting of the tracks 74 to locate these for a wide range of the shift of the carriage 10 78 transversely of the path of travel of the belts 16 and 17.

The carriage 78 at the working side of the machine carries a sectional handle bar 90 supported in brackets 91, and through the medium of the 15 separable coupling 92 of such bar 90 its sections can be freed so that the same can be pushed apart to permit the operator or attendant of the machine to more closely approach the belts 16 and 17 should the carriage be extended toward such 20 operator or attendant or beyond that side of the machine. It will be apparent that when the handle bar is dismantled as before stated, or in normalcy, it will permit the manual shifting of the carriage for the presentation of the work thereon 25 to the belts 16 and 17 during the sanding operation of the machine.

At each side of the carriage 78 there is mounted a stop 93, the portion 94 being adapted for contact with a bumper 95 on one guide 73 to limit 30 the movement of the said carriage in one direction, while the portion 96 of the stop 93 coacts with a bumper 97 on each track 74 so that the carriage will be restricted in its movement in the reverse direction.

35 Each track 74 has fitted thereto resilient bumpers 98, these being arranged beyond opposite ends of the companion guide 73 for said track and thus restrict the throw of such track in reverse directions, the said bumpers 98 being set to prevent the overriding of the rack on said track 74.

Provided on the motors 10 and 11 are bearings 99 in which are pivoted, at 100, reversely set L-shaped brake levers 101, these having the brake 45 surfaces of the pulleys 15 and 30 so that such pulleys can be selectively brought to a standstill. The levers are normally held in neutral position by means of springs 103 and operative upon these levers is a push and pull rod 104 which, through 50 the connection 105, will throw one of the brake levers 101 from neutral to braking position when pushed upon, and through the connection 106 the other brake lever can be moved from neutral to braking position on a pull upon the said rod 104, the free end of the latter being provided with a handhold 107 for convenient manipulation thereof.

It will be understood that the motors 10 and 11 are selectively started and stopped at the will of the operator of the machine and when operating will impart motion to the belts 16 and 17 so that the latter will act upon the work presented by the work supporting stand as the material to be operated upon is presented to the belts at the under 60 faces of the upper stretches thereof.

It should be apparent that by adjustment of the pulleys 15 and 30 the same can be separated or spread sufficiently apart to permit the removal of the belts 16 and 17 therefrom or their replace-

ment, or new ones substituted, as the occasion may require. Also when these belts become dull or worn by reason of their travel in a given direction the motors can be reversed, thus reversing the direction of travel of such belts so that further service of the same may be had for sanding and polishing purposes. It is desirable to have the two belts 16 and 17 travel in opposite directions although, as indicated, they may both travel in the same direction and reverse as to direction at 10 the will of the operator of the machine.

By reason of the anti-slipping surfaces on the pulleys of the machine the abrasive side of the belts 16 and 17 will be prevented from coming in contact with the metal from which these pulleys 15 are made and at the same time such belts will be prevented from sliding upon the pulleys.

The slatted work bed 79 is readily adjustable vertically and transversely to the path of travel of the belts 16 and 17 and thus will properly present the work to the abrasive side of such belts for the sanding and polishing of the work, as should be obvious.

What is claimed is:

1. A machine of the character described comprising a pair of end stands, an intermediate work supporting stand with respect thereto, motor driven abrasive belts supported by said end stands to be disposed in spaced edge to edge relation to each other, means for adjustment of such belts laterally toward and away from each other to vary the edge to edge relation of the same, means independent of the last-named means for truing the belts, one with respect to the other, motors for independently driving each belt and reversing the direction of travel thereof, an adjustable work bed carried by the intermediate stand and movable vertically and laterally with respect to said belts, manually operable means for controlling the movements of the work bed, bumpers associated with the bed to limit the movements thereof transversely with respect to said belts, means for independently braking the momentum of said belts, and a single control for said braking means.

2. A machine of the character described comprising a pair of end stands, an intermediate work supporting stand with respect thereto, motor driven abrasive belts supported by said end stands to be disposed in spaced edge to edge relation to each other, means for adjustment of such belts laterally toward and away from each other to vary the edge to edge relation of the same, means independent of the last-named means for truing the belts, one with respect to the other, motors for independently driving each belt and reversing the direction of travel thereof, an adjustable work bed carried by the intermediate stand and movable vertically and laterally with respect to said belts, manually operable means for controlling the movements of the work bed, bumpers associated with the bed to limit the movements thereof transversely with respect to said belts, means for independently braking the momentum of said belts, a single control for said braking means, and manually operated means for holding the belts in their shifted positions.

DAVID S. OAKLEY.
